AIR HEATER FOR FURNACES

Filed Dec. 27, 1924

UNITED STATES PATENT OFFICE.

HARRY A. IVES, OF BROOKLYN, NEW YORK, ASSIGNOR TO THRIFT FUEL SAVER CORPORATION, OF NEW YORK, N. Y., A CORPORATION OF NEW YORK.

AIR HEATER FOR FURNACES.

Application filed December 27, 1924. Serial No. 758,327.

To all whom it may concern:

Be it known that I, HARRY A. IVES, a citizen of the United States, residing at Brooklyn, New York, in the county of Kings and State of New York, have invented certain new and useful Improvements in Air Heaters for Furnaces, of which the following is a specification.

This invention relates to air heaters for furnaces, and especially to a heating device which may be attached to various types of furnace doors, an object of the invention being to provide an improved air heating attachment which will be simplified in construction, relatively cheap and inexpensive to manufacture, adapted to be readily applied to any standard type of furnace door, and wherein the improved construction is such that the air entering the damper in the furnace door will be heated to a higher degree and at the same time without any substantial obstruction to the passage of the air through the heater into the furnace.

A further object of this invention is to provide an improved air heater adapted to be attached to a furnace door and wherein the heater comprises an inclosing casing having a series of pipes or tubes extending vertically through the heater, the construction being such that the hot gases from the combustion chamber will pass vertically through the pipes or tubes in the heater so that the air entering the damper in the furnace door will contact with these heated pipes thereby enabling the air passing through the heater into the combustion chamber to be heated to the desired extent and at the same time without materially reducing the velocity of the air passing through the heater.

Other objects of this invention will appear in the following description and appended claims, reference being had to the accompanying drawings forming a part of this specification, wherein like reference characters designate corresponding parts in the several views, and wherein Fig. 1 is a vertical section through the furnace door and heater; Fig. 2 is a sectional view taken substantially on lines 2-2 of Fig. 1 in the direction of the arrows; Fig. 3 is a sectional plan view taken substantially on lines 3-3 of Fig. 1; and Fig. 4 is a top plan view showing the top plate of the heater.

Before explaining in detail the present improvement and mode of operation thereof, I desire to have it understood that the invention is not limited to the details of construction and arrangement of parts which are illustrated in the accompanying drawings, since the invention is capable of other embodiments, and that the phrasology which I employ is for the purpose of description and not of limitation.

The purpose of the present improved heating device is to facilitate combustion within the combustion chamber of the furnace and to reduce the consumption of fuel by pre-heating the air passing through the damper of the furnace door into the combustion chamber, thus facilitating the mixing of the air with the hot gases within the furnace. Heretofore in the usual types of heaters for furnaces it has been attempted to increase the heated surface against which the incoming air from the damper contacts by directing the air through a large and circuitous series of passages or convolutions formed in the heater. Although in such types of heaters it was possible to eventually heat the air to a higher temperature, yet it has been found that by passing the air through a long circuitous heating passage provided with large obstructing surfaces the velocity of the air was reduced to a great extent, so that even with the damper in the furnace door wide open the volume of incoming air was small and usually inadequate. In addition to the fact that such heaters supplied an inadequate amount of air to the combustion chamber of the furnace, the construction thereof was necessarily expensive and complicated, which proved to be a serious commercial disadvantage. The foregoing disadvantages have been overcome by virtue of the present invention, wherein the air may be heated to a higher temperature and without materially decreasing the velocity of the air, and wherein the construction is simplified and adapted to be utilized with various types of furnaces.

Referring to the drawings, wherein a present preferred form of my invention is shown, it will be seen that the heating device comprises top and bottom plates or members 9 and 10, which are preferably identical in construction and therefore in-

terchangeable when assembling the parts of the heater. The top plate 9 is provided with a series of holes or perforations 11 and in like manner the bottom plate 10 is provided with a series of holes or perforations 12 similarly arranged so that when the top and bottom plates or members are located in position the corresponding holes or perforations of each plate will be vertically alined.

10 The plates 9 and 10 around the marginal edges thereof are provided with projecting ribs or flanges 13 and 14 respectively. The top plate 9 is provided with a continuous groove 15 adjacent to the flange or rib 13, 15 and the bottom 10 is provided with a similar groove 16.

The top and bottom members 9 and 10 are connected together by means of a casing member 17 which in the present instance 20 forms a continuous vertical enclosing wall. The side enclosure or casing 17 may be formed of sheet metal, and as shown in the present instance is bent into substantially U-shape so that the upper edge thereof will 25 fit into the groove 15 in the top plate 9 and the lower edge will fit into the groove 16 in the bottom plate 10. The outer end of the casing is provided with a suitable vent or opening 18 through which the heated air 30 enters the combustion chamber of the furnace, a depending lip 19 being provided in the present instance to direct the air downwardly into the chamber. As will be seen from the construction the inner end of the 35 casing is open and improved means is provided for releasably attaching the heater to the inner side of the furnace door 20.

A relatively narrow strap or plate 21 is 40 bent at the opposite ends to provide flanges 22 which are riveted at 23 to the opposite inner faces of the member 17. This strap 21 extends transversely across the inner end of the heater and is located intermediate the top and bottom of the heater, as shown 45 clearly in the drawings, and the strap 21 is offset or bent inwardly at 24 away from the damper of the furnace door. An attaching strap 25 is also applied to the outer side of the furnace door 20, this strap or plate 50 having the ends 26 bent so as to lie flush against the vertical face of the door and having the central part offset or bent outwardly at 27 in a manner similar to the offset of attaching strap 21. A bolt 28 is 55 inserted through openings in the damper and furnace door and through alined holes in the straps 21 and 25, and by tightening the nut 29 on the outer end of the bolt the straps 21 and 25 may be drawn together and 60 clamped firmly against the opposite faces of the furnace door. The central oppositely bent portions of the straps 21 and 25 have considerable spring or resilency, so that when the nut 29 is tightened on bolt 28 the 65 straps will be clamped against the faces of

the furnace door under tension, thereby firmly securing the heater to the inner face of the door. Since the bolt 28 may be inserted through the usual openings in the damper of the furnace door it is not necessary to provide any special construction as heretofore in order to attach the heater to the door. The offset portions of the straps 21 and 25 enable the heater to be effectively clamped on to the door under tension so that it will not be displaced, and these offset portions furthermore by being spaced from the damper do not obstruct the passage of air through the openings 30.

Within the heater casing are located a 80 series of pipes or tubes 31. Each pipe is fitted into a pair of alined openings or holes 11 and 12 in the top and bottom plates 9 and 10. In the present instance by way of example, the edges of each opening 11 and 85 12 are beveled off, and the opposite ends of the pipes or tubes 31 are also beveled so as to fit into the openings or perforations, as clearly shown in Fig. 1.

From the foregoing it will be seen that 90 the heater is releasably attached to the inner side of the furnace door 20, the latter being hinged at 32 to the front wall 33 of the furnace. The latter is provided with the usual opening 34 through which the heater 95 extends into the interior of the combustion chamber. It will be seen that the hot gases rising from the bed of fuel on the grate 35 will pass upwardly through the tubes or 100 pipes 31 in the direction of the arrows in Fig. 1. The hot gases will thus heat the tubes or pipes so that the air passing through the openings 30 in the damper and through the heater will contact with the hot walls 105 of the pipes and become heated and will pass out through the vent 18 into the combustion chamber. It will be particularly noted that the present construction enables the greatest utilization of the heat from the hot gases 110 to be obtained since the number of pipes 31 may be proportionately increased toward the outer end of the heater. Thus, as shown 115 particularly in Fig. 3 a larger number of pipes in proportion to the area is provided at the outer end of the heater than at the inner end, at which point the volume of hot gases rising from the fuel bed is greatest and at the same time hottest. From this it 120 will be seen that the air entering through the damper may be gradually and increasingly heated as it passes through the heater. At the same time the velocity of the air passing through the heater is not decreased to any material extent. As shown by the 125 arrows in Fig. 3 the air passing through the heater will be divided into a series of thin streams which will be quickly heated to a high temperature by contact with the pipes located in staggered relation.

It is to be understood that by describing 130

in detail herein any particular form, structure or arrangement, it is not intended to limit the invention beyond the terms of the several claims or the requirements of the 5 prior art.

Having thus explained the nature of my said invention and described a way of constructing and making the same, although without attempting to set forth all of the 10 forms in which it may be made, or all of the modes of its use, I claim:

1. An air heater adapted for attachment to a furnace door having a damper and comprising a casing having an air inlet mouth 15 and an exit for heated air and provided with a transverse passage for the hot furnace gases, and means including resilient means for connecting the casing to the door with the front end of said casing embracing the 20 damper.

2. An air heater adapted for attachment to a furnace door having a damper and comprising a casing having an air inlet mouth and an exit for heated air and provided with 25 a transverse passage for the hot furnace gases, and means including a resilient clamping member for connecting the casing to the furnace door with the front end of said casing embracing the damper.

3. The combination with a furnace door having a damper opening of an air heater, said heater comprising a casing having an air outlet and terminating at one end in an air inlet mouth embracing said damper 35 opening, means for conducting the hot furnace gases through said casing, a spring clamping member housed within said casing and secured thereto, and a bolt connected to said member and extending through said 40 damper opening for detachably connecting the casing to said door.

4. The combination with a furnace door of a heater comprising a casing having top and bottom members provided with pairs of vertically aligned holes, pipes extending through the casing, each pipe having the ends thereof opening into each aligned pair of holes, and means for connecting said heater to the furnace door, the outer end of the heater 50 having a proportionately larger number of pipes than the inner end.

5. The combination with a furnace door of a heater comprising a casing having top and bottom members provided with pairs of vertically aligned holes, pipes extending through the casing and communicating with the several pairs of holes, and yieldable means within said casing for releasably securing the heater to said door.

6. The combination with a furnace door having a damper opening of an air heater, said heater comprising a casing having an air outlet and terminating at one end in an air inlet mouth embracing said damper 65 opening, means for conducting the hot fur-

nace gases through said casing, a spring clamping member housed within said casing and secured thereto, a spring clamping member at the outer side of the furnace door, and a bolt connecting said members together. 70

7. An air heater adapted to be attached to a furnace door and comprising a casing provided with an inlet mouth at one end with the marginal edge thereof terminating against the face of the door, means for conducting the hot combustion gases of the furnace through said heater, and means located within the inlet mouth of the heater for attaching the casing to the furnace door under tension. 75

8. An air heater adapted for attachment to a furnace door having a damper and comprising a casing open at its front end and having an exit for heated air at its rear end, a pair of spaced walls of said casing 80 having a plurality of transverse passages closed to the interior of said casing for the passage of the hot furnace gases, and resilient means for connecting the casing centrally to the furnace door through the damper opening with the open front end of said casing embracing the damper. 85

9. An air heater adapted for attachment to a furnace door having a damper and comprising a casing having an air inlet mouth 95 and an exit for heated air and provided with a transverse passage for the hot furnace gases, and means comprising a bolt and a bowed strap for connecting the casing to the furnace door with the front end of 100 said casing embracing the damper.

10. An air heater adapted for attachment to a furnace door having a damper and comprising a casing open at its front end and having an exit for heated air at its rear end, a pair of spaced walls of said casing 105 having a plurality of transverse passages closed to the interior of said casing for the passage of the hot furnace gases, a greater number of said passages being located toward the rear than toward the front of said casing, and means for connecting the casing centrally to the furnace door through the damper opening with the open front end of said casing embracing the damper. 110

11. A heater adapted to be attached to a furnace door and comprising an enclosing casing having top, bottom and side walls, a series of pipes extending vertically through said casing, each pipe opening at the top and bottom of the casing exteriorly of the latter, and means for releasably connecting the casing to the furnace door, said means comprising a pair of spring members located at opposite sides of the door and adapted to be held together under tension. 115

12. An air heater adapted for attachment to a furnace door having a damper and comprising a casing having an air inlet mouth 120

- and an exit for heated air and provided with a transverse passage for the hot furnace gases, and means for connecting the casing to the furnace door through the 5 damper opening with the front end of said casing embracing the damper and comprising a bolt extending through the door and a bowed resilient clamping member carried by said bolt and engaging said door.
- 10 13. The combination with a furnace door having a damper opening of an air heater, said heater comprising a casing having an air outlet and having at one end an air inlet mouth terminating at the inner face 15 of said door and embracing said damper opening, and means comprising a plurality of vertical ducts for conducting the hot furnace gases through said casing, said ducts being proportionately greater in num-
- ber adjacent to said outlet than adjacent to said inlet.
14. The combination with a furnace door having a damper opening of an air heater, said heater comprising a casing having an air outlet and having at one end an air inlet mouth terminating at the inner face of said door and embracing said damper opening, means comprising a plurality of vertical ducts for conducting the hot furnace gases through said casing, and means extending 25 through said damper opening and connected to the casing interiorly thereof for attaching the casing to said door.

Signed at 1822 Park Row Building, New York, New York, this 26th day of December, 1924.

HARRY A. IVES.
